UNITED STATES PATENT OFFICE.

GEORGE C. HESTER, OF PORTLAND, OREGON, ASSIGNOR TO HESTER MANUFACTURING COMPANY, OF CHICAGO, ILLINOIS, A CORPORATION OF ILLINOIS.

VENTILATED GLASS-SETTING FOR WINDOWS.

1,303,062.

Specification of Letters Patent.

Patented May 6, 1919.

Application filed April 9, 1909, Serial No. 488,962. Renewed December 27, 1916. Serial No. 139,185.

To all whom it may concern:

Be it known that I, GEORGE C. HESTER, of Portland, in the county of Multnomah, and in the State of Oregon, have invented 5 a certain new and useful Improvement in Ventilated Glass-Settings for Windows; and I do hereby declare that the following is a full, clear, and exact description thereof, reference being had to the accompanying drawings, in which—

Figure 1 is a perspective view of a portion of a display window embodying my invention, viewed from the outside;

Fig. 2 is a perspective view of a portion 15 of one of the side bars;

Fig. 3 a perspective view of a portion of the corner bar; and

Fig. 4 a detail view in perspective of one 20 of the corner bar clamps.

My invention relates to window construction suited more especially for display or store fronts, in which the sheets or panes of 25 glass are mounted in bars formed of sheet metal, and the objects of my invention, generally stated, are the efficient and satisfactory ventilation of the window, and the prevention of the collection of moisture or 30 the sweating of the glass, and frosting thereof; the proper cushioning of the glass to prevent its accidental cracking or breaking; and the more convenient erection of the 35 window parts, but without any sacrifice of appearances and strength, and for the accomplishment of the ends or objects that I have in view my invention consists in the window construction substantially as hereinafter specified and claimed.

In the embodiment of my invention illustrated in the drawings, I show a window 40 having, as is common, two panes or sheets of glass 10 arranged at an angle to each other, a corner bar being provided at the angle or corner formed by the two panes of glass, and the side edges of the glass away 45 from the corner bar being supported by vertical sash bars, and the bottom edges by horizontal sash bars, all secured to a framework 11. The vertical and horizontal sash bars are alike in construction. Each 50 consists of two parts, one being a rail 12 of sheet metal that is in the form of a right angle in cross section to engage correspondingly angled surfaces on the framework 11,

and the outer edge of said rail is bent inward at practically a right angle to form 55 a rib or flange 13 which engages one edge of the other member, which is in the form of a rail or bar 14 of sheet metal, that constitutes a glass clamping bar, its other edge being bent to form a longitudinally extending groove 15 that receives a half round cushion strip 16 of wood or other suitable cushioning material, whose flat surface has contact with the surface of the plate of glass. The portion of said rail between its 60 two said edges are inclined away from the inner side of the rail 12, so that when securing screws 17 passing through openings in the clamping rail and through openings in said rail 12 and into the framework 11, 70 are tightened up, they will cause the clamping bar to yieldingly, but nevertheless securely, hold the glass, a sufficient elasticity or spring in the clamping bar being provided to prevent its action upon the plate 75 of glass being too rigid. The cushioning or packing strip 16 will accommodate itself to the position of the glass by rocking in its bearings formed in the clamping bar, even though the angle of the clamping bar 80 changes somewhat. The formation of the clamping bar 14 in cross sections, and its inclination with reference to the side of the rail 12 besides giving a sufficiently yielding nature to the clamp to prevent 85 damage to the plate of glass, forms or provides a channel or space within the sash bar for the circulation of air, and to establish communication between the inside and outside of the window, the contiguous 90 portions of the rail rib 13 and the edge of the clamping bar 14 are provided with alining notches that form small holes 18 that are located at suitable intervals along the sash bar to provide an adequate circulation 95 of air. Besides the cushioning action of the clamping bar, the plate of glass is further cushioned by being placed at intervals in contact with cushions 19 of some soft or yielding metal, such as lead, that are 100 in the form of short bars that are L-shaped in cross section and seated in the corner or angle of the rail 12, so that the edge and side surfaces of the glass have a bearing on said cushions. Besides constituting a yield- 105 ing support for the glass, the cushions 19,

since they are separated from each other, provide air spaces that complete the communication between the inside of the window and the outside of the window for purposes 5 of ventilation. The edge of the cushion member that overlaps the inner surface of the glass is inclined laterally and inward toward the other member of the cushion, so as to avoid the collection of moisture or 10 dust thereon, the angle of inclination being such as will conduce to the ready passage of matter falling on such edge. Instead of making a miter joint where the two clamping bars 13 adjoin each other at a corner, the 15 ends of said bars at such point are cut off or left at a right angle, and the gap or space which thus exists at such corner is covered by an angle piece 20 that conforms to the outer surfaces of the bars and is held 20 in place by the same clamping screws, and such angle piece in itself constitutes a clamp that adds strength to the structure and at the same time enhances its appearance.

For the corner bar, I employ a part-tubular rail 21 of sheet metal that engages the sheets or panes of glass at the corner or angle on the outside thereof, and has its glass-engaging parts formed by inwardly bent ribs or flanges 22, and at intervals there are 25 substantially T-shaped clamping blocks 23, whose fingers or arms are curved to interlock with the inner sides of the glass-engaging ribs or flanges 22, said blocks having each a threaded opening for the reception 30 of a screw 24 passing through a glass-engaging bar or strip 25 that engages the two sheets or panes of glass on their inner surfaces, a strip of felt 26 or other cushioning material being preferably interposed between 35 said clamping bar or strip and the glass. In order to hold the clamping blocks 22 in position for the application of the screws, and yet admit of their ready shifting along the bar or rail 21, to the desired position, I provide on each of said blocks a friction device consisting of a spring 27 fastened thereto and curved or bowed in form, so that it may yieldingly engage the inner 40 surface of the corner bar or rail 21. At the lower end, the bar or rail 21 rests upon a foot 28 that has a vertical bar-engaging member 29 within the same, and an outwardly extending horizontal flange 30 having a hole for a fastening screw 31. The 45 outwardly extending flange 30 of the foot is important in that it enables the glass to be set from outside the window instead of from the inside. In order to cover said foot, and produce a good finish, I employ a quadrant 50 or curvilinear covering piece or molding 32, that at each extremity overlaps the end of the horizontal sash bar contiguous to the corner bar, and is secured in place by screws 33.

65 While I illustrate and have described my

invention as embodied in one structure, it is to be understood that a structure may be made in which all the characteristics or features of my invention will not be embodied, and my claims are to be construed in 70 the light of this statement.

Having thus described my invention, what I claim is—

1. A sash for glass settings comprising a rail of sheet metal that passes beneath the 75 glass plate so as to extend inside and outside the same, said rail having inside the glass an integral up-standing rear flange spaced away from the inner side of the glass, means consisting of members reaching forward from said flange and constituting 80 bearings for the glass on its inner side and above the lower edge of the glass, said members being spaced apart, means for supporting the glass spaced above the portion of 85 said rail forward of said rear flange, providing communication beneath the glass with the spaces inside and outside the same, a bar situated between the outer side of the glass and the upper side of said rail forward of the plane of the outer side of the 90 glass, and means for clamping said bar against the outer side of the glass.

2. A sash for glass settings comprising a rail of sheet metal that passes beneath the 95 glass plate so as to extend inside and outside the same; said rail having inside the glass an integral, up-standing rear flange spaced away from the inner side of the glass, means, consisting of yieldable material, separate from said flange and having bearing contact, at separated points, with said glass, and in advance of said flange, means for supporting the glass spaced above the portion of the rail forward of said 100 flange, a bar situated between the outer side of the glass and the upper side of said rail, and means for clamping said bar against the 105 outer side of the glass.

3. A sash bar for windows comprising a 110 bar or rail having at its edge a projection beyond the glass on one side thereof; a glass holding bar lying between said side of the glass and said projection, and having a 115 glass-engaging member at one edge and a flange at the opposite edge to engage the projection of said rail on the inner side thereof, said glass-holding bar being inclined between its glass-engaging portion and its flange and perforated, and a support for the opposite side of the glass, spaces 120 being between said support and the glass in communication with the space within said bar.

4. The combination of a sash bar, a sheet 125 of glass, and spaced cushioning blocks engaging the edge of the glass, having portions overlapping the side surface of the glass, the outer edge of said portions being inclined.

5. The combination of a channeled sash bar, having openings leading to the channel in the bar, a sheet of glass, and cushioning blocks L-shaped in cross section, to engage
5 the edge and side surface of the glass, spaces existing beyond the cushion blocks, also in communication with the channel in the bar.

In testimony that I claim the foregoing I have hereunto set my hand.

GEORGE C. HESTER.
